UNITED STATES PATENT OFFICE.

WILLIAM CRUTCHLOW, OF PATERSON, NEW JERSEY, ASSIGNOR TO HOLDEN RIGBY, OF SAME PLACE.

KNUCKLE.

SPECIFICATION forming part of Letters Patent No. 625,150, dated May 16, 1899.

Application filed October 8, 1898. Serial No. 692,971. (No model.)

To all whom it may concern:

Be it known that I, WILLIAM CRUTCHLOW, a subject of the Queen of Great Britain, residing in Paterson, in the county of Passaic and State of New Jersey, have invented certain new and useful Improvements in Knuckles for Jacquard-Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to an improvement in flexible connections between the actuating-levers for the griff and card-cylinder of a jacquard-machine and the cranks from which power is transmitted to said levers; and the 20 object of my invention is to provide a device of this nature which shall be simple, cheap, and durable in construction and which shall afford free and practically universal movement between said levers and the cranks.

25 The invention consists in the improved flexible connection and in the combination and arrangement of the various parts thereof with the actuating-levers of a jacquard-machine and their operating-cranks.

30 My invention is fully illustrated in the accompanying drawings, in which like letters of reference indicate parts correspondingly referred to in this specification, and wherein—

Figure 1 is a view in side elevation of a 35 jacquard-machine provided with my improved flexible connection between its actuating-levers and their operating-cranks. Fig. 2 is an enlarged view of a portion of my improved flexible connection, showing the 40 knuckle-joint between the sections thereof; and Fig. 3 is a central vertical sectional view of that portion of the device which is shown in Fig. 2.

Referring to the accompanying drawings, 45 *a* indicates a jacquard-machine suitably supported upon beams *b*.

c and *d* indicate, respectively, the griff and card-cylinder-operating levers, the former being fulcrumed at *d* in the standard *e* of the 50 jacquard-machine and the latter being ful-

crumed at *f* in said standard above the lever *c*. The lever *c* is connected to the griff *g*, which latter is guided, as usual, in any suitable manner by vertical connecting-rods, one on each side of the frame and the nearer one 55 of which is indicated by the reference-letter *g'*, and the lever *d*, which includes an arm *h* and which is therefore practically a bell-crank lever, is connected to and adapted to operate the cylinder *h'* of the machine through guided 60 reciprocating bars or rods *h*² and links *h*³, connecting the upper end of said arm *h* and the rod *h*². The levers *c* and *d* are operated from the shaft *i*, which may be any available shaft 65 of the loom in connection with which the jacquard-machine is to be used. Adjustably mounted on said shaft by means of a set-screw *i'* is a crank *i*², carrying at its free end a crank-pin *i*³. At the outer or free end of said crank-pin is adjustably mounted, by 70 means of a set-screw *k*, an auxiliary crank *k'*.

Between the free end of the crank *i*² and the crank *k'* is journaled on the crank-pin *i*³ a pitman *m*, and journaled upon a crank-pin *k*² at the free end of the crank *k'* is another 75 pitman *n*. Said pitmen are respectively provided at their free ends with integral and offset heads *m' n'*.

Mounted on and penetrated by the levers *c* and *d* are blocks *o o'*, respectively, adjustably secured to the levers by set-screws *o*² *o*³, respectively, and each provided at its lower end with spaced integral and circular enlargements *p p'*.

Connecting-rods *q q'* penetrate the heads 85 *m' n'* of the pitmen *m n*, respectively, and are longitudinally adjustably mounted therein by means of nuts *r*, engaging the threaded ends of the connecting-rods *q q'* and situated on each side of said heads. At the upper 90 end of each of said connecting-rods is a sleeve *s*, provided with an internal screw-threading engaging corresponding threading upon the end of said rod and having integrally formed therewith a pair of spaced circular enlargements *t t'*, similar to the aforementioned enlargements *p p'*. The pairs of enlargements *p p'* and *t t'* are connected by an intermediate member, which consists of a pair of spaced disks *u u'*, integrally formed with a connect- 100

ing and compound web u^2 in such manner that said disks are relatively situated in planes which intersect each other at right angles. The disks are pivotally arranged between the 5 enlargements upon bolts $v v'$, which penetrate said disks and intermediate circular bearings $w w'$, situated in central openings in said disks.

In order to produce as much freedom of 10 movement as possible, the circular bearings $w w'$ are made slightly thicker than the disks. Furthermore, when the bearings are properly bolted together, so that the circular bearings are tightly secured between the disks, no 15 movement will be permitted between said bearings and the bolt, and consequently the strain and wear which would otherwise be borne by the bolt alone is practically taken up by the circular bearings and the disks. 20 The bolt may also share in bearing the strain; but if the parts are clamped together tight enough to prevent any turning of the bearing on the bolt there will be no wear upon the latter.

25 Having thus fully described my invention, what I claim as new, and desire to secure by Letters Patent, is—

1. In a knuckle-joint, the combination of 30 two substantially similar members, said members being disposed in intersecting planes and each comprising a pair of spaced sections, a third connecting member having its extremities pivotally arranged between the sections of each pair, and a bearing situated between 35 said sections and upon which each extremity of said connecting member is pivoted, said bearing being of greater thickness than that of said extremity, substantially as described.

2. In a knuckle-joint, the combination of 40 two substantially similar members, said members being disposed in intersecting planes and each comprising a pair of spaced and integrally-connected circular sections, a third connecting member comprising integrally-connected disks pivotally arranged between the sections of each pair, a circular bearing upon which each disk 45 is pivoted, said bearing being of greater thickness than said disk, and a bolt penetrating said sections of each member and its circular bearing, substantially as described.

penetrating said sections of each member and its circular bearing, substantially as described. 50

3. A flexible connection between a lever of a jacquard-machine and a crank for operating said lever, consisting of a connecting-rod adjustably and operatively connected to said crank and a knuckle-joint consisting of two 55 members, one of said members being adapted to be adjustably connected to said lever and the other of said members being adjustably secured to said connecting-rod, and each comprising a pair of spaced and integrally-connected circular sections, a third connecting member comprising integrally-connected disks pivotally arranged between the sections of each pair, a circular bearing situated between 60 said bearings and upon which each disk is pivoted, said bearing being of greater thickness than that of said disk, and a bolt penetrating said sections of each member and its circular bearing, substantially as described. 65

70 4. The combination with an operating-lever for a jacquard-machine and with a crank for operating said lever, of a pitman pivotally connected to said crank, a connecting-rod adjustably connected to said pitman and a 75 knuckle-joint consisting of two members, one of said members being adjustably connected to said lever and the other of said members being adjustably secured to said connecting-rod, and each of said members comprising a 80 pair of spaced and integrally-connected circular sections, a third connecting member comprising integrally-connected disks pivotally arranged between the sections of each pair, a circular bearing upon which each disk 85 is pivoted, said bearing being of greater thickness than said disk, and a bolt penetrating said sections of each member and its circular bearing, substantially as described.

70 In testimony that I claim the foregoing I have hereunto set my hand this 26th day of September, 1898.

WILLIAM CRUTCHLOW.
